APPARATUS FOR SMOOTHING AND DRYING
GARMENTS

Harry C. Grimes, Elkins, W. Va.

Application February 3, 1943, Serial No. 474,578

5 Claims. (Cl. 38—15)

1

The present invention relates to pressing machines of the type for ironing or smoothing garments.

Heretofore, in so-called "steam laundry," it has been necessary, as well as the practice, to employ four and sometimes five separate machines to press a man's shirt. The method of using these various machines is usually to press the cuffs and collar of the shirt on one machine designed for this purpose; then the shirt is placed upon a bosom pressing machine; from the bosom pressing machine, the shirt is placed upon a yoke pressing machine which irons the back of the shirt under the collar portion; from the yoke pressing machine, the shirt is placed upon a so-called body pressing machine which presses the back and sides and tail sections of the shirt; from the body pressing machine, the shirt is placed upon a form known as a "sleever" (which is an elongated, tapering form, somewhat oblong in cross section, over which the sleeve is slid); and, finally, the shirt is folded.

The broad object of the present invention is primarily to improve the, so-called, bosom pressing machine so that the need of the yoke presser, body presser and "sleever," and the necessary operators, may be dispensed with and so that, when the shirt has left the bosom presser, it is ready to be folded for packaging or delivery to the customer.

More specifically, it is the object of the invention to improve a pressing machine, comprising stationary and moveable bucks, with instrumentalities that will force air into a shirt or similar tubular garment, having one portion resting on the stationary buck or bed and the other portions suspended below said buck, so as to distend the suspended portions of the garment in order that such distended portions will be smoothed and dried by said air while that portion of the garment in contact with the stationary buck is being pressed and dried between the latter and the moveable buck.

With the above and other objects in view, as will appear as the specification proceeds, the invention further resides in the sundry details of construction, combination and arrangement of parts hereafter more fully described and particularly pointed out in the appended claims.

As an example of one form in which the invention may be constructed, reference may be had to the accompanying drawings in which—

Figure 1 is a front elevation of a conventional pressing machine equipped with the present invention;

2

Figure 2 is a plan view of the machine shown in Figure 1, with the top buck removed;

Figure 3 is an end elevation of the machine as shown in Figure 1 and viewed from the right hand side of Figure 1; and

Figure 4 is a top plan view, similar to Figure 2, illustrating a shirt placed in position on the lower buck or bed and in the distended position it assumes when subjected to the action of the present invention.

Referring in detail to the drawings, in which like characters of reference refer to similar and like parts throughout the several views, 10 denotes a supporting standard or pedestal to support a table 11 and stationary buck or bed 12 of a conventional pressing machine, which also includes a complementary upper or swinging buck 13 mounted on a swinging arm 14 pivotally connected to a horn or supporting arm 15 at the rear 15 of the machine. The swinging arm 14 is suitably balanced, as at 16, and is, ordinarily, connected by a link 17 to a treadle 18 at the base of the pedestal 10 and by which an upper buck 13 may be swung into cooperative pressing relation 20 against the upper surface of the lower buck. When pressure is relieved from the treadle 18, the upper buck 13 is raised by the action of the weight 16, or other means such as springs, air, et cetera. A protecting side-board 19 rises from the 25 rear edge of the table 11.

The above description describes the rudimentary principles of a pressing machine and forms no part of the present invention except as they cooperate with the rest of the mechanism later to be described. It will, of course, be understood that the particular construction or form of the pressing machine may vary from that shown and described, as it may be air-operated or electrically operated, and may take any form which employs an upper and a lower buck for pressing purposes. Such bucks contain a heating means usually forming steam chambers, to which steam is supplied, and are covered with padding. Also, some of said pressing machines are equipped with, 30 so-called, exhausting or suction means which carry off vapors, thus tending to dry the pressed portion between the bucks.

Before describing the mechanism of the present invention, it will serve a useful purpose to refer to Figure 4, where a shirt is shown placed in position on the lower buck 12 to have its front portions pressed between the upper and lower bucks, it being understood that the cuffs and collar of the shirt have been previously pressed on another 35 machine. It has been found that, with the shirt

in position on the lower buck, as shown in Figure 4, if air under pressure, and preferably hot air, is blown under the lower buck 12, say at the tail portion of the shirt, particularly while the upper buck is in its lower pressing position against the front of the shirt—so as to hold the shirt on the buck—the back, sides and sleeves can be dried and smoothed to take on an appearance as though they had been pressed with an iron or in a buck pressing machine, the operation taking place at the same time that the front of the shirt is being pressed and dried between the upper and lower bucks 12 and 13.

In order to accomplish the results just mentioned, it is proposed that the support 20, which supports the buck 12 on table 11 and positioned at the end of the lower buck 12 opposite the collar receiving end 21, be cut away as at x, or otherwise so fashioned, that there will be clearance or room for the tail portion of the shirt to be stretched and extended under the buck 12 when the collar of the shirt is placed around the usual collar-form 21.

A pair of air discharging nozzles 22 (which may comprise open-ended air impervious pipes) are arranged on opposite sides of the buck-support 20 between the table 11 and buck 12. These nozzles are positioned to direct a blast of air emitted therefrom longitudinally of the buck 12 in a direction from the tail-end of the shirt on said buck toward the other end thereof. The nozzles 22 are shown as terminating slightly within the open tail-end of the shirt, but satisfactory results are obtained if the terminal ends of the nozzles do not extend within the said end of the shirt. Also, it is within the purview of the invention that there be only one nozzle 22, which may extend through the support 20.

In order to insure that the tail-end of the shirt will remain in position with respect to the lower buck while the hot air is being blown into it, the tail portion of the shirt may be gripped by spring fasteners 35, as shown in Figure 4, these fasteners being of any approved type and being, preferably, carried on the ends of a flexible cord 36 secured to the table 20, as shown in Figures 1 and 4. A baffle plate 34, extending transversely underneath buck 12 terminating a slight distance above table 11, obstructs and retards the outward flow of air from the open tail-end of the shirt caused by back pressure as the air-pressure from the nozzles 22 builds up within the shirt. Of course, as shown, this baffle plate should be positioned short of the terminal discharge ends of the nozzles 22 in the direction of the air flow.

It has also been found, where the back, sides and sleeve portions of the shirt have dried out too much for good results, that by atomizing steam, into the air current from the nozzles 22, for a brief period of time during the operation, the fabric is moistened sufficiently to permit the desired results to be obtained.

To this end, a steam nozzle 23 is shown between the lower buck or bed 12 and the table 11 and, preferably, slightly in advance of the terminal discharge ends of the air nozzles 22; however, the nozzle 23 may be disposed in or incorporated into the air nozzle. As one means of supplying the hot air blast to the nozzles 22, there is shown a fan blower 24, of the centrifugal type, driven from an electrical motor 25, both mounted on the pedestal base of the machine or at another convenient point. Communicating with the intake side of the blower 24 is a heater 26 of any approved construction. This heater may consist of a casing having therein a steam coil 27 so that

air being induced into the fan will pass through the heater 26 to heat the air to at least 140° F. The hot air discharged from the fan 24 is conducted through conduit 28, preferably insulated, connected to the air nozzles 22.

The customary steam supply line for the bucks 12 and 13 has connected thereto a pipe 29 to supply steam to the coil 27 of the heater 24 and also has a pipe connection 30 to the steam nozzle 23. This pipe 30 is provided with a hand valve 31 positioned for convenient operation by the presser or attendant so that steam may be emitted from the nozzle 23 for the purposes above described.

It is proposed that the hot air from the nozzles 22 be discharged only when the garment is on the machine and is having the desired portion of it subjected to the cooperative action of the lower and upper bucks, or when the upper buck 13 is in predetermined position from its uppermost raised position. Therefore, the electrical supply line to the motor 25 has a switch 32 interposed therein to be operated to close the motor circuit when the upper buck 13 is in a predetermined lower position. Any type of switch may be employed for this purpose, but it has been found that a mercury switch is admirably suitable for this purpose.

The present apparatus, when operated as above defined, will introduce a hot air blast into a shirt or other garment or tubular fabric article, when on a pressing machine, so as to distend the fabric thereof by air pressure which seeps through the interstices of the fabric resulting in smoothing out and drying the fabric, producing no wrinkles and leaving the surface of the fabric with a very natural, smooth, laundered finish. In the case of shirts or other garments having sleeves, the above operation is facilitated by closing the ends of the sleeves by clip 33 (Figure 4) or other suitable means—elongated U-shape spring clip or elongated clothes pins serving this purpose very well.

Having thus described the invention and the manner in which it is to be performed, that which is claimed as new is:

1. In a shirt pressing machine, cooperating relatively movable pressing members upon one of which the shirt front is laid with the back, sides and sleeves of the shirt body suspended from said member; a source from which a blast of air is emitted including an air conduit having a discharge end discharging directly into the suspended portion of the shirt below said last mentioned pressing member and in the general direction from the tail end portion of the shirt toward the neck and shoulder end portion thereof to distend said suspended portion of the shirt by said air blast alone while said front portion of the shirt is being pressed between said pressing members, whereby said suspended portion of the shirt may be stretched smooth and dried while its front is being pressed.

2. In a pressing machine, cooperating relatively movable pressing members upon one of which the shirt front is laid with the back, sides and sleeves of the shirt body suspended from said member; blower means for creating a blast of heated air, a conduit for directing said air blast to the under-side of said shirt front supporting member and having a discharge end open to discharge said air blast directly into the suspended portion of the shirt and in a direction from the opened tail-end portion of the suspended portion of the shirt toward its other end to distend said suspended portion of the shirt

by said air blast only, whereby said suspended portion of the shirt may be stretched smooth and dried while its front portion is being pressed between said pressing members, and means controlled by the position of said movable pressing member for controlling the emission and cutting-off of said air blast.

3. In a pressing machine as set forth in claim 1 wherein there is a supply source of fabric-moistening agent, means for causing said moistening agent to become entrained in said air blast within said distended shirt portions, and means for controlling the entrainment of said moistening agent at the will of the operator.

4. In a pressing machine as set forth in claim 1 further characterized by holding means under said shirt front supporting member and positioned to engage the tail-end portion of the back of the shirt to hold the latter in position against the pressure of said air blast.

20

5. In a pressing machine comprising a pair of cooperating pressing bucks having opposed pressing surfaces, one stationary and the other movable toward and from the stationary buck, an electrically driven blower mounted on the machine, an air-impervious conduit receiving the said current of air from said blower and having a discharge end disposed and mounted on the machine at one end of the stationary buck and positioned to direct the air from the blower substantially longitudinally of said stationary buck on the side thereof opposite to its pressing surface, and means controlled by the position of said movable buck to control the emission of said air from the discharge end of said conduit, the discharge end of said conduit being free to discharge into the atmosphere to distend portions of garments suspended below said stationary buck without the aid of intervening means.
